FLASHLIGHT

Frederick J. Berlinger, Cincinnati, Ohio.

Application October 9, 1940, Serial No. 360,422

7 Claims. (Cl. 240—10.68)

This invention relates to improvements in flashlights and is particularly directed to small, portable light-producing means which may be carried in a pocket on one's person or in any other convenient manner.

An object of my invention is to provide a simplified flashlight structure which functions to retain a lamp bulb in a movable carriage and also establish a good, permanent electrical connection between said bulb and the casing in which said carriage moves.

Another object of the invention is to provide an improved manually operable means for actuating a movable lamp carriage to open and close a switching device for the flashlight.

A further object of my invention is to provide a flashlight of the character described which has a few simple parts which may be manufactured and assembled quickly and inexpensively and which operate positively and accurately to accomplish the above outlined functions.

Other objects will become apparent from the following specification and drawings which show a preferred form of my invention and in which:

Fig. 1 is a front elevational view of my flashlight.

Fig. 2 is a fragmental, enlarged, cross-sectional view taken on line 2—2 of Fig. 1.

Fig. 3 is an enlarged cross-sectional view taken on line 3—3 of Fig. 1.

Fig. 4 is a side elevation of the top portion of the flashlight, shown in Fig. 1, with the manually operated sleeve removed therefrom.

Fig. 5 is an enlarged, side elevational view of the lamp bulb carriage for my flashlight.

Fig. 6 is a front elevational view of a modification of my invention.

Fig. 7 is an enlarged cross-sectional view taken on line 7—7 of Fig. 6.

Fig. 8 is an enlarged cross-sectional view taken on line 8—8 of Fig. 6.

The embodiment of my invention consists of a tubular casing 8, preferably made of metal, and having an open top 9 and a closed bottom 10. A plurality of conventional dry cell batteries 11 are positioned within the casing with their capped carbon electrodes in engagement with the bottom of the metal cup of the cell next above. The cup is covered with an impregnated paper, as is well known. The batteries 11 are axially movable within the casing so that they may be inserted therein through the open top 9 and for the purposes to be hereinafter explained.

A lamp carriage 12 is rotatably and axially movable within the casing adjacent the open end

9 thereof. The carriage is cylindrical in form and is provided with a reduced shank-like portion 13, said portion and said carriage having a hollow open-ended center for freely receiving incandescent light bulb 14. As shown in Fig. 2, the reduced portion of the lamp bulb bears against a shoulder defining the division plane between the hollow part of the shank and the hollow part of the carriage proper.

A resilient means is mounted on the carriage for engaging the lamp bulb to maintain it within the carriage and also to engage the interior surface of the casing. This means comprises a leaf spring 15, circular in form, which is disposed in a peripheral groove 16 formed in the carriage. The spring is fastened intermediate its ends to the carriage by means of opposed ears 17 punched in the side walls of the groove after the spring has been inserted therein. As clearly indicated in Figs. 3 and 5, one end of the spring is provided with a finger 18 which extends through an opening 19 formed in the carriage in horizontal alignment with the peripheral groove 16. The finger resiliently presses against the threaded metal end of the lamp which serves as one terminal therefor. As shown in Figs. 2 and 3, the free end of the spring 20 extends into the opening 19 formed in the carriage and bears against the interior surface of the casing.

The exterior portion of the casing adjacent the open end thereof is provided with a manually operated member which is illustrated as sleeve 21. The means for connecting the leaf spring 15 with the manually operated member may consist of an extended portion on the free end 20 of the resilient means and may take the form of a lug 22 fastened to the leaf spring and extending through an inclined slot 23 formed in the casing 8. The lug 22 is received in a hole 24 formed in the sleeve 21.

A spring clip 25 is fastened to the carriage by providing a hook portion 26 thereon for entering a slot 27 formed in the sleeve. The clip is made of spring metal and constantly urges its free end 28 against the exterior portion of the casing.

A switching device 29 for the flashlight comprises an insulation disk 30 having a central aperture 31 and a shank portion 32 through which said aperture extends. A compression spring 33 encircles the shank portion 32 and engages the interior wall of the casing 8. The lower end of the spring is turned upwardly into a contact portion 34 which, when the batteries are axially moved downwardly against the action

of the spring, contacts the bottom of the lowermost battery 11.

The spring is normally adapted to urge the batteries upwardly so that the carbon electrode 35 of the uppermost battery is in contact with the lamp terminal 36. Rotational movement of the sleeve in a clockwise direction, as indicated in Fig. 3 will cause the lamp carriage to be rotated and moved axially in a downward direction, until the bottom of the lowermost battery is engaged by the contact portion 34 of the spring 33 whereby an electric current will be created and pass through the lamp bulb. The lamp is turned off by turning the sleeve in a counter-clockwise direction.

To open the flashlight to replace "worn out" lamps or batteries, the carriage and sleeve are rotated clockwise toward their respective "on" positions and are stopped before said positions are reached. The carriage is then held rigid by manually grasping its shank portion 13 and the sleeve is rotated counterclockwise and the force thereby exerted on the lug 22 will cause the spring to move inwardly, thus disengaging said lug from the hole 24 formed in the sleeve. The sleeve is then removed and by manually pressing the lug inwardly it can be disengaged from the slot 23 and the carriage may be moved axially out of the casing. To assemble the flashlight, the lug is depressed to clear the interior surface of the casing as the carriage is inserted therein and upon alignment of the lug and the slot the lug will snap into it by action of the spring 15. The sleeve is then placed around the casing and the lug depressed to engage the interior of said sleeve. When the lug is in alignment with the hole 24 it will enter it thus completing the assembly of the flashlight.

A modification of my flashlight is illustrated in Figs. 6-8, like parts therein being indicated by reference numerals heretofore used in Figs. 1-5. In this flashlight structure, the lamp carriage 12 is cylindrical in shape and is also provided with a shank-like portion 13. The carriage is hollow for the reception of a lamp bulb 14. The exterior part of the carriage is provided with a peripheral groove 38 into which the upper edge 39 of the sleeve 210 is crimped to rigidly fasten the carriage to said sleeve. As shown in Fig. 7, the portion of the sleeve below its connection with the carriage extends outwardly so as to provide sufficient clearance between its interior and the exterior of the carriage for insertion therebetween of the upper edge of the casing 8. The casing is adapted for free relative movement between the sleeve and the carriage and is provided with an inclined slot 40 narrower than the slot 15 in the flashlight illustrated in Figs. 1-5. The slot is adapted to receive the upper end 41 of spring clip 25, said end being resiliently held therein by action of the clip and adapted to extend through a hole 24 formed in the sleeve. The clip is formed to lie beneath a raised portion 42 formed in the sleeve and to then have a return bend portion 43 constituting a manual release lever for the clip. The lower end 28 of the clip is normally urged against the exterior of the casing 8.

The lamp 14 is held in the carriage by means of a leaf spring 44 which is U-shaped in cross-section and disposed around the lower edge of the carriage. The spring is fastened to the carriage by forming a horizontal cut 46 in the lower part of the carriage, entering the spring therein, and then forcing the portion between the edge

of the carriage and the slot against the spring to rigidly clamp said spring in position. The legs of this spring are urged outwardly away from the wall of the carriage, the interior leg serving to hold the lamp in the carriage. The other leg of the spring resiliently engages the interior of the casing. The spring therefore establishes a good electrical connection between the lamp and the casing. The lower portion of the flashlight is the same as that illustrated in Figs. 1-5 and therefore need not be described again.

To disengage the carriage and sleeve from the upper end of the casing for replacing batteries or a lamp, it is only necessary to raise the upper end 41 of the clip out of the groove 40 formed in the casing and move the parts away from each other. The end 41 may be raised out of the slot 40 by inserting a tool or other means between the adjacent portion of the clip and the sleeve and prying or otherwise moving said end out of the slot against the action of said spring clip. The preferred means of accomplishing the separation of the flashlight is to form the end 41 of the clip with a tapered end having rounded corners as illustrated in Fig. 8. To move the end out of the slot would then require a rotational force greater than that used to normally turn the light "off" and "on," said force causing the tapered end to ride out of the slot and over the exterior portion of the casing of the upper edge thereof for disengagement of the parts. To again return the parts to operative position, I form a notch 45 in the upper edge of the casing, which is adapted to receive the end 41 of the spring and thereafter upon rotation of the sleeve, the end will ride up on the casing until brought over the slot where it will snap into said slot under the inherent action of the resilient clip 25.

What is claimed is:

1. In a flashlight the combination of a cylindrical casing having a closed bottom end and an open end, a battery axially movable within the casing, a cylindrical carriage axially and rotatably movable within the casing and disposed adjacent the open end thereof, a lamp bulb held in the carriage and in contact with the battery, a switch between the bottom of the casing and the battery, a spring in the bottom of the casing for biasing the battery, lamp and carriage to open switch positions, a manually operated means rotatably and axially movable exteriorly of the open end of the casing for actuating the carriage, means for establishing a constant electrical contact between the lamp and the casing and means for operatively connecting the manually operated means and the carriage, said member upon operation being adapted to axially move the carriage, lamp and battery to closed or open switch positions.

2. In a flashlight the combination of a cylindrical casing having a closed bottom end and an open end, a battery axially movable within the casing, a lamp bulb in contact with the battery, a cylindrical carriage axially and rotatably movable within the casing and disposed adjacent the open end thereof, said carriage having a central opening therethrough for enclosing the lamp bulb, a switch between the bottom of the casing and the battery, a spring in the bottom of the casing for biasing the battery, lamp and carriage to open switch positions, a ring rotatably and axially movable exteriorly of the open end of the casing for actuating the carriage, means for operatively connecting the ring and the carriage, said ring upon manual operation being adapted to axially

move the carriage lamp and battery to closed or open switch positions, and a spring mounted on the carriage in resilient engagement with the lamp bulb, said spring also resiliently engaging the casing to form an electrical connection between said bulb and casing and to provide a sliding, frictional connection between the carriage and said casing.

3. In a flashlight the combination of a cylindrical casing having a closed bottom end and an open end, a battery axially movable within the casing, a lamp bulb in contact with the battery, a cylindrical carriage axially and rotatably movable within the casing and disposed adjacent the open end thereof, said carriage having a central opening therethrough for enclosing the lamp bulb, a switch between the bottom of the casing and the battery, a spring in the bottom of the casing for biasing the battery, lamp and carriage to open switch positions, a ring rotatably and axially movable exteriorly of the open end of the casing for actuating the carriage, means on the carriage extending through the casing for operatively connecting the ring and the carriage, said ring upon manual operation being adapted to axially move the carriage, lamp and battery to closed or open switch positions, and a spring mounted on the carriage in resilient engagement with the lamp bulb, said spring also resiliently engaging the casing to form an electrical connection between said bulb and casing and to provide a sliding, frictional connection between the carriage and said casing.

4. In a flashlight the combination of a tubular casing having a closed bottom end and an open end and an inclined slot formed therethrough adjacent said open end, a battery axially movable within the casing, a lamp bulb in contact with the battery, a switch between the bottom end of the casing and the bottom of the battery, a spring in the bottom of the casing for biasing the battery to open switch position, a cylindrical carriage axially and rotatably movable within the casing and disposed adjacent the open end thereof, said carriage having an axial bore therethrough for enclosing the lamp bulb and having a peripheral groove formed therein, a peripheral opening formed in said carriage in alignment with the groove, a circular leaf spring fastened intermediate its ends in the groove, one end of said spring formed with an inturned finger which extends through one side of said opening for resilient engagement with the lamp bulb, and having its free end disposed in the opposite side of said opening and adapted to resiliently engage the interior of the casing, a lug on the free end of the spring and resiliently held thereon in a position to extend through the slot and beyond the casing, a rotatable switch operating sleeve member around the exterior of the casing and having a hole therein for receiving the lug, said member upon man-

ual rotation thereof being adapted to axially move the carriage, lamp and battery to open or closed switch positions.

5. In a flashlight the combination of a tubular casing having a closed bottom end and an open end, an inclined slot formed in the casing adjacent its open end, a battery axially movable within the casing, a switch positioned between the battery and the bottom of the casing, a lamp bulb in contact with the battery, a cylindrical lamp bulb carriage axially and rotatably movable within the casing, means in the bottom of the casing for biasing the battery and carriage to open switch position, a spring mounted on and encircling the carriage and engaging the bulb and the casing, a lug on the spring resiliently held in a position to extend through the slot and beyond the casing, and an axially and rotatably movable switch operating sleeve member on the casing having a hole therein for receiving the lug, said sleeve member upon manual operation being adapted to move the lamp carriage and the battery to open and close said switch.

6. In a flashlight the combination of a cylindrical casing having a closed bottom end and an open end, a battery axially movable within the casing, a cylindrical carriage axially and rotatably movable in the casing and disposed adjacent the open end thereof, a lamp bulb held in the carriage and in contact with the battery, a switch between the bottom of the casing and the battery, a spring in the bottom of the casing for biasing the battery, lamp and carriage to open switch positions, means for establishing a constant electrical contact between the lamp and the casing, and a sleeve member rotatably and axially movable exteriorly of the open end of the casing and having a top edge united to the upper portion of the carriage whereby upon manual operation of the sleeve member the carriage, lamp and battery are moved to their closed or open switch positions.

7. In a flashlight the combination of a tubular casing having a closed bottom end and an open end, an inclined slot formed in the casing adjacent its open end, a battery axially movable within the casing, a switch positioned between the battery and the bottom of the casing, a lamp bulb in contact with the battery, a cylindrical lamp bulb carriage axially and rotatably movable in the casing, means for establishing an electrical contact between the bulb and the casing, a sleeve member axially and rotatably movable exteriorly of the open end of the casing and having a top edge united to the upper portion of the carriage, and a resilient clip mounted on the sleeve and having a free end extending into the inclined slot whereby upon manual operation of the sleeve member the carriage, lamp and battery are moved to their closed or open switch positions.
